DESIGN FOR A HANDLE FOR A BURIAL CASKET

William Zaiser, Rockville Centre, N. Y., assignor to New York & Brooklyn Casket Co., Brooklyn, N. Y., a corporation of New York

Application May 28, 1942, Serial No. 107,040

Term of patent 7 years

To all whom it may concern:

Be it known that I, William Zaiser, a citizen of the United States, residing at Rockville Centre, county of Nassau, and State of New York,
have invented a new, original, and ornamental Design for a Handle for a Burial Casket, of which the following is a specification, reference being had to the accompanying drawing, forming part thereof.

Fig. 1 is a perspective view of a handle for a burial casket embodying my new design.

Fig. 2 is an end view of the same.

Fig. 3 is an enlarged sectional view taken on the plane of the line 3—3 of Fig. 1.

I claim:

The ornamental design for a handle for a burial casket, as shown.

WILLIAM ZAISER.
